CLAIM

The ornamental design for a cordless screwdriver, as shown.

DESCRIPTION

FIG. 1 is a perspective view of my novel cordless screwdriver;

FIG. 2 is a top plan view of my novel cordless screwdriver;

FIG. 3 is a side view of the right side, when viewed from the

screw bit receiving end of my novel cordless screwdriver;

FIG. 4 is a side view of the left side, when viewed from the

screw bit receiving end of my novel cordless screwdriver;

FIG. 5 is a bottom plan view of my novel cordless screw-

driver with the screw bit receiving end facing to the right;

FIG. 6 is a rear view of my novel cordless screwdriver; and,

FIG. 7 is a front view onto the screw bit receiving end of my novel cordless screwdriver.
